(57) **CLAIM**

The ornamental design for a bi-view cabinet, as shown and described.

DESCRIPTION

FIG. 1 is a perspective view of a bi-view cabinet showing my new design;

FIG. 2 is a front elevational view thereof;

FIG. 3 is a left side view thereof, the opposite side being a mirror image of the side shown;

FIG. 4 is a top plan view thereof; and,

FIG. 5 is a perspective view thereof with a cabinet door open.
